FRANKFURTER SANDWICH PLATE

Harry Silos, Fairfield, Conn.

Application September 28, 1956, Serial No. 43,146

Term of patent 14 years

(Cl. D44—15)

Fig. 1.

Fig. 2.

Fig. 3.

Fig. 4.

Fig. 1 is a perspective view of a frankfurter sandwich plate, showing my new design;

Fig. 2 is a top plan view thereof;

Fig. 3 is a bottom view;

Fig. 4 is an end view, and

Fig. 5 is a central longitudinal section.

I claim:

The ornamental design for a frankfurter sandwich plate, substantially as shown.
